UNITED STATES PATENT OFFICE.

ERNEST PRICE, OF EAST NORWALK, CONNECTICUT.

SPRINKLER.

979,199.

Specification of Letters Patent. Patented Dec. 20, 1910.

Application filed May 17, 1909. Serial No. 496,628.

To all whom it may concern:

Be it known that I, ERNEST PRICE, a subject of the King of Great Britain, residing at East Norwalk, county of Fairfield, State 5 of Connecticut, have invented an Improvement in Sprinklers, of which the following is a specification.

This invention relates to sprinklers adapted for general use as in laundries and famili- 10 lies for sprinkling articles of clothing, bed linen, etc., before ironing, for sprinkling plants and wherever it is desired to scatter small drops of water or other fluid evenly, and the invention has for its object to pro- 15 vide a simple and inexpensive self-filling hand sprinkler adapted for general use, which will fill without appreciable loss of time and will hold the water or other fluid so that it will escape therefrom in small 20 drops by movement of the sprinkler and which may be filled and used without wetting the hand.

With these and other objects in view I have devised the novel sprinkler of which 25 the following description in connection with the accompanying drawing is a specification, reference characters being used to indicate the several parts:

Figure 1 is an elevation of my novel 30 sprinkler, illustrating the mode of filling; Fig. 2 an elevation illustrating a modification in details of construction; and Fig. 3 is an inverted plan view of my novel 35 sprinkler.

It is an important feature of the invention that the device is complete in itself and is without detachable parts.

The device comprises essentially a hollow 40 metallic body, indicated by A, which is provided with small perforations 10 for filling and to permit escape of water when the sprinkler is moved about, and a handle B. The special design or configuration of the body is not of the essence of the invention, 45 likewise it is unimportant how it is made; for example, it may be drawn and formed from a disk of metal as brass, or it may be formed from a sheet of tin plate or brass with the edges soldered together.

In the form illustrated in Fig. 1, the bottom and sides of the body are formed integral and the handle indicated specifically by 50 11 is turned from wood and is provided with

a head or plug 12 which just fits into the open upper end of the body to which it is 55 rigidly secured as by nails 13.

In the form illustrated in Fig. 2, the handle, specifically indicated by 14, is formed from a strip of relatively heavy sheet metal and is riveted to a cap 15 which 60 is soldered or riveted to the upper end of the body. 16 denotes a metallic loop which is preferably riveted or soldered to the upper end of the body and serves as a handle for hanging the sprinkler when not in use 65 or for hanging it for filling over the edge of a pail, pan or other receptacle, indicated by 17, for containing water or other fluid to be used in sprinkling.

The operation is as follows: The body is 70 filled with water or other fluid to be used in sprinkling by simply submerging it in the fluid, atmospheric pressure causing the body to fill with water when submerged in about two seconds. The perforations 10 in 75 the body permit the fluid to enter freely under atmospheric pressure but are so small that the water or other fluid can only escape in small drops even when the sprinkler is moved about. In use in sprinkling clothes, 80 the operator may hang the sprinkler over the edge of a receptacle containing water, as in Fig. 1, while arranging the clothes for sprinkling, and then perform the sprinkling operation and then replace the sprinkler in 85 the water ready for another operation, thus keeping sufficient water in the sprinkler so that it will always be ready for use and no time will be lost in filling it.

Having thus described my invention I 90 claim:

A self filling sprinkler comprising a cylinder having its entire periphery perforated, and an integral perforated bottom wall, a 95 separate head permanently secured in the open end of said cylinder to form a closure therefor, a handle secured to said head, and a suspending hook secured to one end of said cylinder whereby the same may be suspended in a body of liquid to fill the sprinkler. 100

In testimony whereof I affix my signature in presence of two witnesses.

ERNEST PRICE.
